US0D1101637S

(12) **United States Design Patent** (10) Patent No.: **US D1,101,637 S**
(45) Date of Patent: ** Nov. 11, 2025

(54) **GRILLE SURROUND**

(71) Applicant: **PACCAR Inc**, Bellevue, WA (US)

(72) Inventors: **Jonathan S. Duncan**, Seattle, WA (US); **Amanda Koh**, Kenmore, WA (US); **Peter Vurpillat**, Seattle, WA (US); **Chris Small**, Seattle, WA (US); **John Jackson**, Sammamish, WA (US); **Rebecca Kern**, Kent, WA (US)

(73) Assignee: **PACCAR Inc**, Bellevue, WA (US)

(**) Term: **15 Years**

(21) Appl. No.: **29/948,936**

(22) Filed: **Jun. 24, 2024**

Related U.S. Application Data

(60) Continuation of application No. 29/761,165, filed on Dec. 7, 2020, now Pat. No. Des. 1,036,321, which is a division of application No. 29/644,078, filed on Apr. 13, 2018, now Pat. No. Des. 906,902.

(51) LOC (15) Cl. **12-16**

(52) U.S. Cl.

USPC **D12/163**

(58) **Field of Classification Search**

(57) CLAIM

The ornamental design for a grille surround as shown and described.

DESCRIPTION

FIG. 1 is a perspective view of a grille surround showing our new design.

FIG. 2 is a front elevational view thereof.

FIG. 3 is a top plan view thereof.

FIG. 4 is a left side elevational view of thereof; and,

FIG. 5 is a right side elevational view thereof.

The broken lines shown in the drawings depict portions of the grille surround that form no part of the claimed design.
